(57) CLAIM

We claim the design for a bench top for dental office, as shown and described.

DESCRIPTION

FIG. 1 is a top and plan view of a bench top showing our new design;

FIG. 2 is a top and front perspective view of the bench top; FIG. 3 is a top and front perspective view of a first variant of the bench top;

FIG. 4 is a top and front perspective view of a second variant of the bench top;

FIG. 5 is a top and plan view of a third variant of the bench top; and,

FIG. 6 is a top and front perspective view of the bench top of FIG. 5.

The portions of the drawings shown in broken lines indicate surrounding structure which does not form part of the design.
